ABSTRACT OF THE DISCLOSURE

Crusher-separator apparatus salvages firm, discrete particles from an admixture thereof with softer materials, e.g. a cranberry harvest, by crushing the softer particles without crushing the firm particles to be salvaged and then discharges the material against a bounce target (an endless conveyor) at an angle of incidence which bounces the firm particles in one general direction for collection separate from the remainder of the material which remains on the target and is continuously moved out of the target area for separate collection.

This invention relates to separating and grading of vegetable material, particularly cranberries, preparatory to its use in the preparation of industrial food products and is concerned more particularly with salvaging firm unbroken cranberries which have obstinately refused to succumb to other separating and grading operations and hence still remain unseparated from soft, infirm, or broken berries.

Oftentimes there are only a few unseparated firm berries in a large bulk of previously separated and graded material, but their recovery is still economically desirable if it can be accomplished with a high percentage of recovery.

To this end, this invention takes advantage of the bounce characteristics of the desired firm cranberries and the strength of the berry shell and subjects the whole bulk to crushing pressure by a means which will not crush the firm berries but which will crush the remaining material and then propels the whole bulk against a bounce board target from which the firm bounceable berries bounce in one general direction and from which unbouncing material is conveniently removed in another general direction.

The crushing means comprise a pair of opposed movable surfaces, preferably rolls, mounted for rotation on horizontal parallel axes, which form a passageway through which the bulk material is passed at a sufficient velocity to propel it as it emerges with sufficient force against the target to bounce the firm berries, but not unduly splash the softer material.

The bounce board is inclined to the path of the propelled material and may be conveniently formed by an endless conveyor belt, which continuously moves through the target area in an upward inclined direction to carry the material collecting on the conveyor surface out of the target area and to permit the harder berries to bounce due to the inclination of the target in a downward direction towards and off the lower end of the conveyor for removal.

Apparatus for performing the separation contemplated by this invention is shown in the accompanying diagrammatic drawing wherein there is an input feed belt 10 at the top of the apparatus which carries cranberry discard from a previous separation operation that has removed most of the whole unbroken cranberries, but still contains some

2

firm, high grade, whole berries which somehow have survived previous operations.

A spreader 12 having brush-like flexible tongues may be added when under full load on fluctuating input and serves to spread the material into a fairly even uniform layer which is discharged off the end of the conveyor on top of a double bank of opposed crushing rolls 16, 17 and 18, 19 supported in tandem vertical relation and mounted on parallel horizontal axes and forming a succession of nips through which the material is passed with a trajectory which assures that the material falls between the converging moving surfaces of rolls 16 and 17.

The rolls are faced with compressible material which can be, for example, a surface layer of polyethylene closed cell foam having a density which will not crush the good berries, backed up by a firmer layer of vinyl foam, for example, rollers having a 21 $\frac{1}{4}$ inch diameter may have the outer polyethylene layer about 1 $\frac{1}{4}$ inches thick and the underlying vinyl layer about 1 inch thick.

Each of the pairs of rolls is subject to adjustment towards and away from each other and while they may not actually contact each other, it is preferred that in operation they do contact each other as reliance is placed upon the compressibility of the foam material not to crush the firm berries but to crush less firm materials dependent upon the pressures used. Normally, with the above compressible surfacing, good operation has been obtained by setting 21 $\frac{1}{4}$ inch diameter rolls in the upper bank on 21 $\frac{1}{2}$ inch centers and in the bottom bank on 21 $\frac{1}{2}$ inch centers, though it is contemplated that different settings for the top and lower rolls may be used, for example, a somewhat smaller setting on the lower rolls to give slightly increased pressure on the second nip. It will be understood that opposed belts may be substituted for the rolls. Motor M is shown as driving only one roll of each pair, but it will be understood that rolls 16 and 18 may also be positively driven, particularly if it is desired to operate with minute gaps at one or both of the nips.

Pairs of scrapers or wipers 20 are associated with both pairs of rolls beneath the respective nips so as to direct the passing material downwardly and clean the roll surfaces.

The rolls may be operated, for example, at a speed of 500 or more feet per minute with the result that the material is forcibly ejected downwardly towards an underlying belt conveyor 30 which has an upwardly inclined path of movement at an angle dependent upon its adjustment in vertical stanchions 31 about a lower pivot support 33. Most of the stream of material collects on the conveyor 30 and is carried up and discharged off the end of the conveyor into a bin 34 with the conveyor belt 30 being cleaned by a scraper 32 for the next revolution.

The firm berries, on the other hand, bounce, on impact on the conveyor 30 and, due to the angle of incidence, take flight in one or more bounces to the left as seen in the drawing off the bottom end of the conveyor 30 where they may be spray washed as from a bank of nozzles 40 and collected on a cross-conveyor 50.

By the above means, a very speedy and efficient recovery of good quality berries may be secured from a large bulk of material in a short time while insuring by crushing adjustment of the rolls that damaged berries will not retain any sufficient amount of bounce, but will rather be so crushed that they no longer bounce as discrete particles and therefore are relegated to being retained on the conveyor and removed upwardly with the discard material.

As will be understood, in some cases the foregoing crusher separator may be used prior to other separation procedures in order to rid the material of cranberries which are defective due to frost, but normally it is contemplated that crusher separation will be utilized only after other pre-separation procedures have been used.

We claim:

1. Apparatus for recovering and separating discrete, relatively firm vegetable particles from an admixture thereof with relatively softer material comprising
 a pair of opposed movable elements mounted for movement through paths forming a nip therebetween, 5
 said elements having compressible surfaces resiliently yieldable to pass said firmer particles through said nip without crushing the same,
 means for moving said elements to pass said admixture 10 through said nip with said firmer elements being maintained uncrushed and forceably propel said admixture away from said nip,
 an inclined target surface spaced from said elements and intersecting the path of said admixture after it is 15 propelled away from said nip,
 means for moving said surface continuously through the target zone and upwardly of said inclination to convey the portion of said admixture which is intercepted by and collects on said inclined surface upwardly in one direction, separated from firmer particles of said admixture which due to the angle of incidence bounce off said surface in a downward direction, and
 means for collecting particles of said admixture which 20 bounce off of and are not moved upwardly on said conveying surface.
2. Apparatus as claimed in claim 1, wherein said target surface is a surface of an endless conveyor belt and wherein said apparatus has means for continuously removing material collecting on said endless belt from said belt during movement of said belt through a portion of its path beyond said target zone.
3. Apparatus as claimed in claim 1 having additional opposed movable elements having compressible surfaces supported in tandem relation with said pair of opposed movable elements and forming an advance nip through which said material passes before it passes through the succeeding nip of said pair of elements.
4. The method of separating and recovering discrete relatively firm bouncable vegetable particles from an admixture thereof with relatively softer material comprising

exerting crushing pressure on a continuously advancing bulk of the admixture at a value less than the pressure required to crush the firmest particles in said admixture and propelling the admixture against a bounce board target surface angularly intersecting the path of said propelled admixture to bounce the uncrushed particles in one general direction determined by the angle of inclination of the target area of the bounce board surface, and
 continuously carrying the softer remainder of the admixture which collects on said surface generally in another direction out of the target zone of the bounce board surface, and
 continuously separately collecting particles bounced off said surface and the said soft remainder.

5. The method claimed in claim 4 wherein sufficient crushing pressure is exerted on said particles in the nip between two opposed rolls to crush the uniform berries and not to crush the firm berries and the rolls move at a speed sufficient to propel said firmer particles as they emerge from between said rolls toward said bounce board surface with a velocity sufficient to cause them to bounce out of the target area of said bounce board surface but at a velocity less than that which would cause any substantial portion of the softer components of said material to splash off said bounce board surface.

6. The method as claimed in claim 5 wherein the bounce board surface continuously moves through the path of said admixture to carry the softer remainder out of the target zone.
